(57) **CLAIM**

The ornamental design for a wrench organizer as shown and described.

DESCRIPTION

FIG. 1 is a front, left and top perspective view of a wrench organizer, showing my new design.

FIG. 2 is a rear, right and bottom perspective view thereof.

FIG. 3 is a bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is another front, left and top perspective view of the wrench organizer of FIG. 1 shown in an environment of use. The dashed broken lines depict portions of the wrench organizer that form no part of the claimed design. The additional dashed broken lines in FIG. 10 depict environmental structure and form no part of the claimed design.
